UNITED STATES PATENT OFFICE.

CHARLES S. PROUDFOOT, OF WESTMONT BOROUGH, AND DAVID L. EYNON, OF ST. DAVIDS, RADNOR TOWNSHIP, DELAWARE COUNTY, PENNSYLVANIA.

SIDE FRAME FOR CAR TRUCKS.

Application filed February 24, 1923. Serial No. 620,892.

To all whom it may concern:

Be it known that we, CHARLES S. PROUDFOOT, a resident of the borough of Westmont, in the county of Cambria and State of Pennsylvania, and DAVID L. EYNON, a resident of St. Davids, Radnor Township, in the county of Delaware and State of Pennsylvania, both citizens of the United States, have invented certain new and useful Improvements in Side Frames for Car Trucks; and we do hereby declare the following to be a full, clear, and exact description of the invention, such as will enable others skilled in the art to which it applies to make and use the same.

Our invention relates generally to an integrally constructed side frame for car trucks which is preferably formed of one plate of metal, such as steel or iron, which plate is first cut and punched to the shape desired for the various members, then bent on its median line to form a hollow structure, with side portions spaced apart and provided with inwardly projecting flanges in some parts, and some of the members are also provided with integral tongues and the companion flanges forming parts of the other sides of said members are provided with outwardly projecting integral portions having grooves therein, which tongues are positioned in said grooves and held firmly therein by close contact in such a way as to secure said members together. These tongues and grooves may extend the full lengths of the members, or preferably may only be formed on portions thereof, as may be desirable.

The pedestal tie bar portions of our side frame are also formed integrally and the inner portions thereof are preferably of channel section with outwardly projecting flanges secured together by means of tongues and grooves as above mentioned, while the end portions are flat and cut into shape in such a way that one is superimposed on the other, one of the flat portions extending from one side and the other from the other side and each provided with registering journal box bolt holes, the inner channel-shaped portions of said pedestal tie bars being secured together by tongues and grooves similar to those above mentioned.

One of the particular features of our invention resides in the manner of connecting the two side portions by means of the

integrally formed tongues and grooves. Some of these tongues may be formed on one portion and some on the other, and the portions which form the grooves may also be formed partially on one of the sides and others on the other side to thereby hold the two sides together. 60

Having thus given a general description of our invention, we will now, in order to make the matter more clear, refer to the annexed sheet of drawings, which forms part of this specification, and in which like characters refer to like parts:—

Figure 1 is a side elevation of a little more than one-half of the left hand portion of our side frame; Figure 2 is a complete bottom plan view thereof, looking upwardly; Figure 3 is an end elevation of the frame of Figure 1; Figure 4 is a central vertical cross section on the line IV—IV of Figure 1; Figure 5 is a cross section on the line V—V of the diagonal tension member at its tongue and groove connection; Figure 6 is a horizontal cross section through one of the column guides taken on the line VI—VI of Figure 1; Figure 7 is a horizontal cross sectional plan taken on the line VII—VII of Figure 4 through the lower portion of the column guides; Figure 8 is a bottom plan view of the end of one of the pedestal tie bars with the grooved connecting portion formed integrally therewith; Figure 9 is a bottom plan view of the end portions of one of the pedestal tie bars with the connecting tongue formed integrally therewith; Figure 10 is a view of the right hand portion of a modified form of our side frame in which the diagonal tension member has overlapping flanges, instead of flanges secured by a tongue and groove, and Figure 11 is an end elevation corresponding to Figure 10. 70 75 80 85

In Figure 1 the wheels, journals, journal box bolts and reinforcing plates are indicated by dotted lines.

Referring now to the characters of reference on the drawings:—1 is the upper portion of the top arch bar of our side frame; 2 are the side portions formed integral therewith and extending therefrom in substantial parallelism and spaced apart; 3 are openings shown as circular between the column guides and the ends of the frame, the boundaries of which are formed by the inturned flanges 4 which project in-

wardly of the structure with their edges spaced apart; 5 are the inturned bottom flanges of the central portion of the top arch bar, the edges of which are spaced 5 apart as shown particularly in Figure 4; 6 is the bolster opening, which is of the usual form, wider at the bottom than at the top to receive the spring plank and the springs mounted thereon, while the bolster 10 is slidably mounted on the springs in the upper portion of said opening adapted to be guided by the bolster guides 8, which are shown as plates welded to the upper portions of the flanges 7 of the column 15 guides in the upper part of the bolster opening; 9 are the upper flanges of the central portion of the bottom arch bar, which are inturned as shown with their edges spaced apart; 10 are the bottom in-turned flanges of the end portion of the frame, the edges of which are contiguous and may be welded together and are adapted 20 to be seated upon the journal boxes; 11 are the inturned flanges projecting inwardly 25 from the lower sides of the diagonal tension members, one of which is provided with the integral tongue portion 12 and the other with the groove portion 13, which are adapted to be secured together thereby as 30 illustrated particularly in Figure 5; 14 are the lower inturned flanges of the bottom arch bar, one of which is provided with an integral tongue portion 15 and the other with an integrally formed groove portion 35 16 adapted to secure the two parts together, as particularly illustrated in Figure 4; 17 are the end portions of the pedestal tie bars, which are formed rights and lefts, as 40 illustrated in Figures 8 and 9, provided 0 with registering journal box bolt holes 18, while one of these has a tongue portion 15 which is adapted to be seated in the grooved portion of the integral extension 16 of the other part. The tongue and groove connections 5 of the two sides of the bottom arch bar and the inner portions of the pedestal tie bars are all numbered 15 and 16, respectively, as these parts form one substantially continuous portion of our frame. 20 0 are the reinforcing plates inserted within the end extension of the frame, provided with upturned lip portions adapted to serve as nut locks for the journal box bolts, and these are secured or welded to the interior 5 of the frame as indicated at 21, and 19 are journal box bolt holes in the upper end portion.

As illustrated in Figure 7, 22 is the spring plank shown in dotted lines, which 0 may be of channel shape, secured to the frame in any manner desired and adapted to tie the two frames of each side of the truck together and to support the customary springs, etc.

5 As illustrated in Figures 10 and 11, the

lower inturned flanges of the end portions are 23 and are arranged to overlap each other as shown, while the integral inturned flanges of the diagonal tension members are 24 and overlap each other similarly, and these need not be secured together, but we may weld or otherwise secure them if desired.

By reason of our construction the various portions of the frame which are necessary to be secured together are so secured by means of the integral tongue and groove connections, thus obviating any welding whatsoever for this purpose, and this tends toward economy and ease of construction while supplying a hollow structure which is strong in all its parts and well adapted for the use intended.

Although we have shown and described our invention in considerable detail, we do not wish to be limited to the exact and specific details thereof as shown and described, but may use much modifications in, substitutions for, or equivalents thereof as are embraced within the scope of our invention, or as pointed out in the claims.

Having thus described our invention, what we claim and desire to secure by Letters Patent is:—

1. A side frame formed integral from one plate, certain members of which are secured together by tongue and groove connections.

2. A truck frame composed of one metal plate, having a top portion, two side portions extending therefrom and spaced apart, some of the members having inwardly extending flanges provided with tongue and groove connections, whereby they are secured together.

3. A truck frame composed of one metal plate, having a top portion, side portions extending therefrom and spaced apart, parts of said side portions having inwardly extending flanges provided with outwardly extending tongue and groove portions interlocking with each other, whereby the parts are secured together.

4. A truck frame composed of one metal plate, including a top portion, a bottom portion, side portions composed of members connecting the same, said side portions being spaced apart and some of them being provided with inturned flanges, some of said flanges having grooved portions and others tongue portions located therein, whereby the parts are firmly secured together.

5. An integral frame for car trucks, composed of a single plate of metal forming the various members thereof, having a top member, side members extending from the upper member in substantial parallelism and spaced apart, a bottom member, inwardly extending flanges on certain of said

members co-operating with each other, one of the same having a grooved portion and the other a tongue adapted to interlock and thereby secure the parts together.

6. A side frame for car trucks of the integral arch bar type, comprising a single plate of metal bent about its intermediate portion, forming a top arch bar, a bottom arch bar, inclined tension members, column guides, and pedestal tie bars, certain of said members having inturned flanges adapted to contact with each other, one of each of said flanges being provided with an integral tongue portion and its companion having an internal grooved portion adapted to interlock, whereby the parts are firmly secured together.

7. A side frame for car trucks, comprising a single plate of metal bent about its intermediate portion, forming a top member, a bottom member, and side members, the sides of which are spaced apart, some of them having inturned flanges, portions of said flanges being provided with integral tongues, and integral grooves in the adjacent portions, adapted to interlock and secure them together.

8. A truck frame composed of one metal plate, having a top portion, a bottom portion, and two side portions extending therefrom connecting them and spaced apart, some of the members forming said side portions being provided with tongue portions and others with grooved portions, all formed integral therewith and extending throughout parts of their lengths, whereby they are firmly secured together without welding or riveting.

9. A side frame for car trucks, composed of a single plate, cut in the shape desired to form the various members, including a top arch bar, a bottom arch bar, inclined side tension members, column guides, and pedestal tie bars, the side portions of which connecting the arch bars are spaced apart and provided with inturned flanges, some of which are opposite and spaced apart, and some with abutting flanges provided

with tongue and groove portions, whereby they are secured together.

10. In an integral arch bar type of side frame, composed of a single plate cut and bent to form the various members thereof, a pedestal tie bar formed integral therewith, portions being formed from one side and others from the other side of the plate and adapted to be overlapped, the inner portion of the tie bar being of channel section with its two parts secured together by a tongue and groove.

11. An integral side frame of the arch bar type formed of a single plate bent on its median line with side portions spaced apart and extending downwardly therefrom, shaped to form the various members, including end portions adapted to rest on the journal boxes, a top arch bar, inclined tension members merging into the ends of said top arch bar and forming end extensions adapted to rest on the journal boxes, a bottom arch bar with integrally formed pedestal tie bars forming end continuations thereof, column guides extending in an upright direction and joining the top and bottom arch bars, openings between the column guides and the end members, a central bolster opening, integrally inturned flanges formed on the various members, some of which are abutting and some of which are spaced apart, and connections between some of the flanges of the various members comprising an integrally formed tongue on one of the inturned flanges and a bent portion forming a groove on the companion flange, these being nested together to form a lock joint, whereby the parts are firmly secured together.

12. A side frame for a car truck, composed of various members, portions of some of which are provided with outstanding flanges secured together by integral tongue and groove connections.

In witness whereof we hereunto affix our signatures.

CHARLES S. PROUDFOOT.
DAVID L. EYNON.
